WHEELED TOY

Samuel Warren, New York, N. Y.

Application April 12, 1929. Serial No. 354,488

6 Claims. (Cl. 46—48)

This invention relates to wheeled toys and particularly to toys which may be inverted or reversed without altering their utility.

Toys of all kinds are subjected to severe usage and it very often happens that the wheels of such toys are pulled off or broken or the axles to which the wheels are secured are bent or broken so that the life of the toy is comparatively short.

The general object of the invention is to provide a wheeled toy which is sturdy and durable and which at the same time is attractive to a child.

A specific object of the invention is to provide a wheeled toy in which the wheels are protected to prevent injury to the wheels or the axles upon which the wheels are mounted.

Other objects and features of the invention will be apparent from the following description of the preferred forms of the invention illustrated in the figures of the drawing.

In the drawing—

Figure 1 is a plan view of a toy embodying the present invention;

Figure 2 is a side view of the form of the invention illustrated in Figure 1;

Figures 3 to 7 inclusive are plan views of modified forms of the invention;

Figure 8 is a side view of a further modification of the invention; and

Figure 9 is a plan view of the form of the invention illustrated in Figure 8.

In the figures of the drawing the toy is shown as comprising a frame or body 2 which is preferably formed of a thick block of wood capable of with-

standing severe usage. The toy is provided with wheels 4 located on both sides of the frame 2 near the ends thereof and supported upon the axles 6 which are shown as extending all the way through the frame or body 2 and projecting from the sides thereof.

The frame 2 is provided with blocks 8 located between the front and rear wheels 4 on each side of the frame and of a width somewhat greater than that of the wheels 4. The frame is also provided with end frame members 10 which project beyond the frame 2 and beyond the wheels 4.

Side frame members 12 extend lengthwise of the toy and are firmly secured to the blocks 8 and the end frame members 10 so as to provide parallel slots 14 near one end of the frame and simi-

lar parallel slots 15 near the other end of the frame within which the wheels 4 are located. The ends of the axle 6 are secured to the side members 12 thereby providing a support for the outer ends of the axles upon which the wheels 4 are mounted.

In this construction the axles 6 upon which the wheels 4 are supported are not exposed so that they will not be broken or injured by the child in playing with the toy. Furthermore, the axles are supported on both sides of the wheels, thus providing an unusually sturdy construction.

The wheels 4 are of greater diameter than the thickness of the body 2 so that they project above and below the remaining parts of the toy, thereby permitting the toy to be operated in inverted positions. The side frame members 12 protect the wheels against the abuse and damage to which the wheels of such toys are ordinarily subjected.

The frame or body 2 is provided with holes or recesses 16 into which the child may insert sticks or flags or other articles to add to the pleasure which the child derives from the use of the toy. These holes should not pass all of the way through the frame so that the sticks or articles inserted therein will not fall through or project below the frame to interfere with the operation of the toy.

The toy is provided with an eye bolt or screw 18 to which a string 20 may be secured to draw the toy along in the manner of a cart. The upper surface of the frame 2 is preferably flat so that a child may place upon it blocks or other toys so that it can be used as a cart or wagon for conveying playthings from one point to another. The toy is preferably wide and low thereby diminishing the tendency for the toy to upset or be turned upon its side. The width of the frame preferably exceeds the diameter of the wheels.

The forms of the invention illustrated in Figures 3 to 7 inclusive are modifications of that illustrated in Figures 1 and 2, although in each case the wheels are carried in slots in the frame of the toy and the axles are supported and protected on the outer sides of the wheels to retain the sturdy construction characteristic of the invention.

In the form of the toy illustrated in Figure 3, the frame 2 and the end frame members 10 and side frame members 12 are substantially the same as those illustrated in Figure 1. However, the slots 14 in which the wheels are located are continuous from end to end of the frame 2 and the blocks 8 shown in Figure 1 are omitted.

The modification illustrated in Figure 4 is substantially the same as that illustrated in Figure 1 with the end frame members 10 omitted. The modification in Figure 5 is similar to the form of the invention illustrated in Figure 1 but the blocks 8 are formed integral with the side frame members 12 and secured to the body 2 as a unit.

In Figure 6 a toy is illustrated in which the frame 2 and side frame members 12 of the toy are formed in one piece and the slots 14 and 15 are formed in the ends of the toy, the end frame members 10 being omitted.

5 The form of the invention illustrated in Figure 7 is similar to that shown in Figure 6 but the end frame members 10 are secured to the ends of the frame 2 so that the slots 14 and 15 within 10 which the wheels 4 are located are closed.

10 The modified form of the invention illustrated in Figures 8 and 9 embodies features which may be incorporated in any or all of the other forms of the invention. In this form the toy is formed 15 with a horizontal slot 24 in one or both ends of the frame or body 2, into which slot a bar or link 26 may be inserted to connect two or more of the 20 toys in a series to represent a trailer or train of cars. A pin 28 projects through the slot 24 and passes through a hole in the end of the bar 26 to hold the bar in place. The bar 26 is flat and of 25 slightly less thickness than the height of the slot 24. The slots in each of the frames are located in substantially the same plane so that the frames 30 2 when formed with only two wheels, as illustrated, will not tip up about their axles, but will be held in a substantially horizontal position. The link connection may be used to join two or 35 more of the four wheeled forms of the toy but is preferably employed with the two wheeled type illustrated since the toy in this form can turn corners more readily than is the case with four wheeled toys. The use of the link for connecting two or more toys in a series does not alter the invertible characteristics of the toy thus rendering it possible for children to enjoy train-like 40 toys when too small to manipulate more complicated and delicate constructions.

The forms of the invention illustrated are merely 45 illustrative of the numerous constructions in which the present invention may be embodied, and therefore it is not intended that the invention should be limited to any particular form of frame or body or to any of the specific constructions illustrated and described except as defined by the following claims.

What is claimed as new is:

1. A wheeled toy having a frame of substantially greater width than height and formed with 50 slots located adjacent its lateral edges, and wheels mounted in said slots to rotate substantially co-axially and spaced in the direction of the axes thereof, the frame extending between the wheels and outside of the wheels and the wheels extend-

ing above and below the frame so that the operative position of the toy may be inverted.

2. A wheeled toy comprising a central frame member, side frame members extending along each side of the frame, means for securing the side frame members to the central frame member in spaced relation thereto, and wheels mounted in the spaces between the central and side frame members and extending substantially equal distances above and below the frame, the frame surrounding the wheels horizontally to protect the same from injury.

3. A toy having a frame comprising a central frame member, longitudinal side frame members extending along each side of the frame in spaced relation thereto, spacing blocks interposed between the side frame members and the central frame member for spacing the same, means for securing together the central frame member, the side frame members and said spacing blocks, wheels mounted in the spaces between the central frame member and the side frame members and extending above and below the frame, axles for said wheels extending across said spaces and engaging in the central frame member and the side frame members.

4. A toy having a frame comprising a central frame member, longitudinal side frame members extending along the opposite sides of the central frame member in spaced relation thereto, end frame members extending along the ends of the central frame member and the side frame members and connecting the same, wheels mounted in the spaces between the central frame member and the side frame members and extending above and below the frame and horizontally enclosed by the central frame member, the side frame members and the end frame members.

5. A toy comprising a plurality of frames, a pair of wheels for supporting each of said frames mounted to rotate co-axially, and means for connecting the frames arranged to limit the tilting movement of the frames about the respective axes of the wheels during the operation of the toy.

6. A toy comprising a plurality of frames, a pair of wheels for supporting each frame mounted to rotate co-axially and extending above and below the frame, and links for connecting the frames arranged to limit the tilting of the frames about the respective axes of the wheels during the operation of the toy.
